UNITED STATES PATENT OFFICE

1,955,548

TIE SPACING DEVICE

Frank J. Jakoubek, Elmwood Park, Ill., assignor to
Templeton, Kenly & Co., Limited, Chicago, Ill.,
a corporation of Illinois

Application December 27, 1932, Serial No. 648,929

4 Claims. (Cl. 254—43)

This invention relates to improvements in tie spacing devices and it consists of the matters hereinafter described and more particularly pointed out in the appended claims.

5 The tie spacing device with which my invention is more particularly concerned, is of the kind illustrated in the Graham and Young patent, No. 1,836,753, of December 15, 1931, and which includes a tie engaging lever and a rail engaging

10 member providing a fulcrum for said lever.

In said patent, the rail engaging or gripping member is of an inverted U-shaped structure and one side arm thereof carries a laterally extending spindle and the other side arm thereof is made 15 with an integral hook-like lip or lug adapted to engage with the lower face of the head or ball of the rail when said member is tilted in the direction of the rail into gripping relation therewith.

20 It is well known that the rails employed in railroad tracks are of different sizes, according to the kind and amount of traffic thereon. Where heavy loads are hauled, the rails have a greater cross sectional dimension and these are manifested 25 in height of rail, width of base and depth of head or ball.

With a structure such as shown in said before-mentioned patent, a number of different sized devices must be included in the track equipment 30 of the maintenance crews of the railroads, to be operative upon the different size rails which may be embodied in track. This increases the cost of track maintenance as it requires the carrying of several different sizes of devices in stock.

35 One of the objects of the present invention is to improve the construction of such a tie spacing device whereby the device may be employed upon rails of all standard sizes and, therefore, the number of such devices required to be carried, 40 may be considerably reduced, with a resulting proportionate saving.

Another object of the invention is to so construct the rail engaging member of the device that it may be readily adapted for use in connection 45 with rails having heads or balls of different perpendicular dimensions.

Still another object of the invention is to so form the rail engaging member that it will receive any one of a number of different sizes of gripping jaws or blocks so that the device may be readily fitted to the rail upon which it is to be used.

Still a further object of the invention is to so 55 form the rail engaging member and jaw that the jaw may be readily removed therefrom and a different sized one substituted in its stead to meet the conditions at hand.

The above mentioned objects of the invention, 60 as well as others, together with the many ad-

vantages thereof, will more fully appear as I proceed with my specification.

In the drawing:

Fig. 1 is a view in end elevation of my improved tie spacing device in operative relation 65 with respect to an associated rail and tie.

Fig. 2 is a view in side elevation of the same and illustrates in dotted lines the position of the parts when spacing or shifting a tie.

Fig. 3 is a view in side elevation of the rail 70 engaging member of the device on an enlarged scale, a portion of the same being shown as broken away and in section to more clearly illustrate the construction thereof.

Fig. 4 is a perspective view of one of a number 75 of gripping jaws or blocks which may be applied to the rail engaging member.

Fig. 5 is a diagrammatic view illustrating the position of the rail head engaging shoulder or ledge of different gripping jaws whereby the device may be used upon a rail of any of the standard cross sections to make the device one of universal application.

In general, my improved tie spacing device includes a lever-like tie engaging member and a 85 rail engaging member. The rail engaging member, which is also provided with a tilting or canting lever, is substantially of an inverted U-shape. Said member includes side arms of different lengths, the longer arm carrying a laterally extending fulcrum spindle or stub shaft for the tie engaging member and the shorter arm being formed to receive rail head or ball engaging jaws or blocks of different sizes, according to the size 90 of the rail upon which the device is to be used. 95 Preferably, said shorter arm is formed in its inner face with a longitudinal groove providing opposed shoulders and each jaw that is used with the rail engaging member has a rib to engage in said groove and be secured therein as by a bolt 100 extending through said arm and into said jaw. By removing the bolt, the jaw may be removed and another of the proper size substituted in its stead.

Referring now in detail to that embodiment of 105 the invention illustrated in the accompanying drawing, 1 indicates as a whole, the rail engaging member of the device and 2 indicates the tie engaging member of the same. The rail engaging member is substantially of an inverted U-shape 110 and includes laterally spaced, long and short side arms 3 and 4 respectively, and a connecting top member 5, the latter being suitably formed to receive a lever-like handle 6.

The long arm 3 includes a spindle or stub 115 shaft 7 near its bottom end and which spindle or stub shaft extends laterally in a direction outwardly away from the short arm 4. In the inner face of said short arm is formed a longitudinally extending groove 8 and on the outer face of said 120

short arm, centrally disposed with respect to said groove is a boss 9. An opening 10 is arranged in said arm between said boss and groove.

11 indicates a gripping jaw in the form of a substantially L-shaped block fitting the inner face of the short arm 4 and having a longitudinal rib 12 along one side adapted to snugly fit in the groove 8. Along the bottom of the other side of said jaw is an inwardly extending ledge 13. The top face of said ledge is arranged at an angle to the horizontal corresponding to the angle of the bottom face of a rail head and which angle is substantially constant and standard in rails of all sizes. Extending laterally through said jaw, is a screw threaded opening 14.

The jaw 11 may be inserted endwise in place in said short arm with its rib engaged in the groove, after which a bolt 15 is passed through the opening 10 in said arm to engage in the opening 14 in the jaw. When the bolt is drawn up tight, the jaw is securely held in place.

The tie engaging member 2 is in the form of a lever of the first class and includes a body 16 having a bearing hub or sleeve on its inner face for an engagement on the spindle or stub shaft 8 on the rail engaging member. When said body is so mounted on said stub, it is held against movement by a washer and nut 17.

The top or power end of said body is formed to receive a lever 18 and the bottom or load arm and tie engaging end 19 of said member is formed with a somewhat rounded head to engage a tie.

In applying the spacer as a whole to a rail 20, it is so applied from the short arm side which is hooked over the rail and with the levers 6 and 18 arranged in the same perpendicular plane. By grasping said levers and imparting opposite movements thereto in the direction of the rail, the rail engaging member is slightly canted so that the shoulder or ledge 13 engages with a non-slipping grip against the underside of the head or ball 21 of a rail. In said movement the load arm end of the tie engaging member engages the tie 22 and moves the same in the desired direction with respect to the rail, as is best shown in dotted lines in Fig. 2. If desired to get a new bite or grip on the rail, the levers 6 and 18 are brought back into the position shown in Fig. 2 and the whole device is shifted along the rail 50 toward the tie when the operation proceeds, as before described.

It is well known that different railroads employ different sizes of rails in their track and a certain road may use different sizes of rails in different portions of its track, in accordance with the traffic thereover. Thus, if a maintenance crew works upon a track using a relatively light rail, the jaw 11 is removed and a new one substituted in its place wherein the ledge is arranged closer to the top of the jaw. This difference in height of the ledges in different jaws, as well as width of said jaws, is best illustrated in dotted lines in Fig. 2. If the duties of the maintenance crew then take them to another section wherein heavier rails are employed in track, it is not necessary to carry along all sizes of tie spacers. When the field of new operations is reached and with the size of rail known, the jaw block 11 is removed from the short arm 4 and another one, to fit the heavier rail, is substituted therefor. This may be quickly done by first removing the bolt 15, taking out the old block 11, replacing another one of the desired size and reapplying the bolt.

Again, if a jaw becomes broken or battered after long use, it is not necessary to replace the entire rail engaging member by a new one. All that is necessary is to remove the broken or battered jaw and substitute a new one. It is apparent that replacement of a jaw is not as expensive as the replacement of a rail engaging member as a whole, so that a material saving is had in this respect. Again, with my improved construction, the maintenance crew need not carry with them a special size tie spacing device for each size of rail found in their section. Thus, tool cost and carrying cost are reduced.

It is apparent that in the tilting or canting of the rail engaging member into gripping engagement on the rail a heavy shearing strain would be imposed upon the bolt if it were not for the interengaging groove and rib arrangement described. Thus, said rib not only removes the shearing strains from said bolt, but it also holds the jaw against any tipping or rocking about said bolt as an axis.

While in describing my invention, I have referred in detail to the form, arrangement and construction of the various parts thereof, the same is to be considered in an illustrative sense only, so that I do not wish to be limited thereto except as may be specifically set forth in the appended claims.

I claim as my invention:—

1. A tie spacing device embodying therein a rail engaging member including laterally spaced side arms, means for pivotally mounting a tie engaging member on one of said side arms, a rail head engaging member associated with the other arm, said rail head engaging member and said other arm being formed with interengaging groove and rib construction arranged parallel with said rail, and means for removably securing said rail head engaging member in operative relation with respect to said other arm.

2. A tie spacing device embodying therein a rail engaging member including laterally spaced side arms, a tie engaging member fulcrumed on one of said side arms, a jaw element including a shoulder along one side thereof for engaging the underside of the head of said rail, means providing interengaging groove and rib on the other side of said element and the inner face of said other side arm respectively, arranged in the direction of the rail, and means for removably securing said jaw and other side arm together in operative relation.

3. A tie spacing device embodying therein a rail engaging member including laterally spaced side arms, a tie engaging member fulcrumed on one of said side arms, a jaw element including a shoulder along one side thereof for engaging the underside of the head of said rail, and a rib on the other side arranged parallel with said shoulder for engagement in a groove provided in the inner side of said other side arm and a bolt extending through said other side arm from the outside thereof and operatively engaging with said jaw.

4. In a tie spacing device, a rail head engaging jaw having a shoulder along one side adapted for engagement with the bottom of one side of said rail head and having a rib on the other side and parallel with said shoulder, there being a transverse, centrally arranged hole in said jaw and opening through said rib at the middle thereof.

FRANK J. JAKOUBEK.
